H. H. C. GRONDAHL

MOLDING APPARATUS

Filed Sept. 3, 1926

UNITED STATES PATENT OFFICE.

HANS HENRIK CHRISTIAN GRONDAHL, OF CHICAGO, ILLINOIS, ASSIGNOR TO WESTERN ELECTRIC COMPANY, OF NEW YORK, N. Y., A CORPORATION OF NEW YORK.

MOLDING APPARATUS.

Application filed September 3, 1926. Serial No. 133,315.

This invention relates to molding apparatus, and more particularly to a multi-mold metal casting apparatus.

The object of the invention is to provide a molding apparatus wherein a plurality of articles may be molded in a single operation and in which the several parts of the apparatus may be readily secured together or separated with a minimum expenditure of time and effort.

In accordance with the general features of the invention, in one embodiment thereof there is provided a framework which pivotally supports a plurality of brackets upon which are mounted a plurality of sets of mold sections designed to contact with each other, the adjacent ones of the oppositely disposed sets contacting with a vertical intermediate plate also supported by the framework, to form slab mold chambers for receiving molten material. Quick-acting clamping means grip the mold sections tightly in operative position and quickly release them to permit the removal of molded articles.

It is believed that the invention will be clearly understood from the following detailed description taken in connection with the accompanying drawing illustrating one embodiment of the invention, and in which

Fig. 1 is a front elevation, partially broken away, of a molding apparatus embodying the invention;

Fig. 2 is a side elevation thereof;

Fig. 3 is a plan view thereof showing the several parts in operative position, and

Fig. 4 is a fragmentary plan view showing several of the parts in open position.

In the drawing in which like numerals designate similar parts throughout the several views, the numeral 10 designates a foot plate in which are mounted standards 11 and 12 which are braced at intervals by straps 13-13 and cross bars 14-14, which latter also form securing means for fastening the framework formed by the foot plate, standards, straps, and cross bars to a supporting member, such as a wall 15. The cross bars 14-14 are also provided with channel-shaped members 16 midway between the standards 11 and 12 in which is mounted a vertical, forwardly extending plate 18.

Detachably and pivotally mounted on the standard 11 are brackets 20 and 21 which are

connected to each other by a brace 22. In 55 order to make the brackets removable, the bracket 21 is provided with a fork-shaped end which is designed to partially encircle the standard 11 while the bracket 20 is provided at one end with a circular aperture 60 through which the upper end of the standard 11 is inserted. A plurality of mold sections 23-23 are pivotally mounted upon the brackets 20 and 21 by means of arms 24-24, which arms are of unequal lengths to permit 65 wide separation of the mold sections. Similar brackets 25 and 26 and mold sections 27-27 are also mounted upon the standard 12. The mold sections, arms and brackets are so designed that when swung into operative position, as shown in Fig. 3, the inner mold section of each set contacts with the plate 18 and each of the remaining sections coacts with the mold section immediately in advance of it to form a mold 70 chamber.

The mold sections are secured in operative position by means of quick-acting clamping devices which are pivotally mounted upon the standards 11 and 12. A 75 plurality of arms 30-30 are pivotally secured at one end to the standard 11 and a plurality of similar arms 31-31 are pivotally mounted upon the standard 12, each of which arms is provided with a plurality of 80 openings 33-33 in one of which is mounted a shoe 32 for engaging the outer mold section of the associated set. The outer ends of the arms 30-30 are fork-shaped and a plurality of square nuts 34-34 are pivotally mounted therein. A plurality of yokes 85 35-35 are also inserted in the fork ends of the arms 30-30, which yokes are provided at one end with central threaded holes 36-36 into which are screwed the large 90 portions of differential screws 38-38 which are provided with hand wheels 39-39, while the small portion of the differential screws 38-38 engages the nuts 34-34. Links 40-40 are attached at one end to the 95 yokes 35-35 and are provided at the opposite ends with loop portions 41-41 which are designed to overlap the forward ends of the arms 31-31, also fork-shaped, and which pivotally carry a plurality of hooks 100 43-43, the ends of which may be encircled by the loop portions 41-41 of the links 40-40.

105

The operation of the apparatus is as follows: The mold sections 23-23 and 27-27 are swung inwardly until the inner sections contact with the plate 18 and the other sections contact with each other in the position shown in Fig. 3, the arms 30-30 and 31-31 are then swung inwardly until the shoes 32-32 contact with the backs of the outer of the mold sections 23-23 and 27-27, the loop end portions 41-41 of the links 40-40 are then swung over the hooks 43-43 and the latter are forced backwardly into the position shown in Fig. 3 until the loop end portions 41-41 are back of the centers 15 of rotation of the hooks 43-43. The hand wheels 39-39 are then rotated in the proper direction to turn the differential screws 38-38 to tension the links 40-40, thereby forcing the arms 30-30 and 31-31 inwardly to 20 cause the shoes 32-32 to grip the mold sections tightly in operative position. Molten material may then be poured into the mold chambers formed by the coaction of the mold sections and the plate 18, and allowed 25 to remain until the material solidifies when the hooks 43-43 may be moved forwardly until the loop end portions 41-41 are released and the links 40-40 may be withdrawn. The arms 30-30 and 31-31 and 30 the mold sections 33-33 and 27-27 may then be swung outwardly in the position shown in Fig. 4 in order that the slabs of solidified material formed therein may be removed.

35 By using a differential screw for tightening the links, it is possible to exert a clamping force on the molds equivalent to that obtainable with a screw of very fine pitch without sacrificing the strength inherent in 40 a screw of coarse pitch, while the provision of separable molds pivotally mounted on arms of unequal length makes it possible to separate the mold sections widely and to remove the molded slabs formed therein 45 with a minimum of time and effort.

The above described embodiment of the invention is particularly adapted for molding slabs of non-ferrous metals which are to be subsequently formed into various shapes, 50 but it is to be understood that the above figures are illustrative only and that various modifications in the size and arrangement of parts may be made without departing from the scope of the invention. For example, 55 the brackets and their supported mold sections might be replaced by other brackets supporting fewer sections, in which case, spacers might be substituted for some of the sections so that the same clamping 60 means could be used. The length of the mold sections may be varied as desired within the total length of the apparatus, and the width of the sections may also be changed if desired, it being possible to locate the gripping shoes on the clamping

arms centrally of the sections by shifting them into alignment with the proper opening in the arms.

What is claimed is:

1. In a molding apparatus, a framework including uprights, a vertical and forwardly extending plate supported by the framework, brackets pivotally mounted on the uprights, a plurality of separable mold sections carried by said brackets designed 75 to cooperate with said plate and with each other to form mold chambers, and quick-acting mold clamping elements carried by said uprights for securing the mold sections in operative position.

2. In a molding apparatus, a plurality of separable mold sections, and quick-acting mold clamping means comprising a pair of arms provided with shoes for engaging 85 the outer of the mold sections, a link carried by one of the arms to connect the arms, and differential screw means for tensioning the link to cause the shoes to grip the mold sections tightly in operative position.

3. In a molding apparatus, a framework 90 including two uprights, a vertical and forwardly extending plate supported by the framework midway between the uprights, a pair of brackets pivotally mounted on each upright, each pair of brackets pivotally supporting a plurality of separable mold sections designed to cooperate with said plate and with each other to form mold chambers, and mold clamping elements carried by said uprights for securing the mold 95 sections in operative position.

4. In a molding apparatus, a framework including two uprights, a vertical and forwardly extending plate supported by the framework midway between the uprights, a 105 pair of brackets pivotally mounted on each upright, each pair of brackets pivotally supporting a plurality of separable mold sections designed to cooperate with said plate and with each other to form mold chambers, and quick-acting mold clamping means carried by the uprights comprising a pair of arms provided with shoes for engaging the outer mold sections, a link carried by one of the arms to connect the arms, and differential screw means for tensioning the link to cause the shoes to grip the mold sections 110 tightly in operative position.

5. In a molding apparatus, a framework, a vertical plate supported thereby, a plurality of separable mold sections designed to cooperate with the plate and with each other to form mold chambers, and quick-acting mold clamping means comprising a 120 pair of arms pivotally mounted on said frame provided with shoes to engage the outer mold sections, a yoke carried by one of the arms, a link pivotally attached to the yoke and provided with a looped end portion to overlap the end of the other arm, 125 130

and differential screw means for tensioning the link to cause the arms to force the shoes tightly against the mold sections to secure the sections in operative position.

5. 6. In a molding apparatus, a vertical plate, a plurality of molds having arms of successively increasing lengths, a movable bracket for pivotally supporting the arms

of the molds, and means for positioning the molds with relation to the vertical plate to 10 form a plurality of mold cavities.

In witness whereof, I hereunto subscribe my name this 13th day of August, A. D. 1926.

HANS HENRIK CHRISTIAN GRONDAHL.
